UNITED STATES PATENT OFFICE.

HERMAN P. ANDRESEN, OF CHICAGO, ILLINOIS, ASSIGNOR OF ONE-HALF TO DAVID J. EVANS,
OF CHICAGO, ILLINOIS

GRAB-BUCKET AND OPERATING MECHANISM.

No. 870,812.

Specification of Letters Patent.

Patented Nov. 12, 1907.

Application filed November 5, 1906. Serial No. 342,087.

To all whom it may concern:

Be it known that I, HERMAN P. ANDRESEN, a citizen of the United States, and resident of Chicago, Cook county, Illinois, have invented a certain new, useful, and Improved Grab-Bucket and Operating Mechanism, of which the following is a true, exact, and clear description, such as will enable others skilled in the art to which it appertains to make and use the same.

My invention relates to new and useful improvements in grab buckets commonly known as clam shell grabs, and also relates to improvements in the operating mechanism employed for manipulating such buckets.

The object of my invention is to provide improved means for excavating and hoisting such materials as iron ore, coal and the like.

The special objects of my invention are to provide an improved grab bucket, which shall be strong and durable; which may be operated with a minimum expenditure of power; which shall have a large spread or reach; which when opened and lowered upon the material shall present substantially vertical cutting edges thereto, thereby insuring the sinking of the bucket into the material; which notwithstanding its great spread or reach shall be of minimum height when in hoisting condition, *i. e.* when closed; which shall be so constructed that it will close upon and dig into the material with great power and certainty; which shall be of such form that the bucket parts proper shall constitute the largest portion of the device, to the end that a grab bucket of maximum capacity may be worked in an opening or hatch of minimum size, without limitation by or interference from the mere operating parts of the bucket; which shall be of such form and so attached to its operating cables that the bucket may be worked beneath the overhanging edges of a hatch opening, deck or covering inclosing the material to be moved; and finally, which shall be of very simple construction, comprising few parts of comparatively low cost.

Further objects of my invention are to provide a clam shell or grab bucket which shall be capable of being swung or rotated to any desired position and to provide simple and effective means for raising, lowering, positioning and swinging or turning the bucket from a single overhead point, *i. e.* from and by means of the hoisting engine or machinery proper.

Still further objects of my invention will appear hereinafter.

My invention consists generally in a grab bucket and operating mechanism therefor, all as hereinafter described and particularly pointed out in the claims.

The invention will be more readily understood by reference to the accompanying drawings, forming a part of this specification and in which;

Figure 1 is a perspective view of a grab bucket and operating mechanism embodying my invention; Fig. 2

is a vertical section of the grab bucket, the dotted lines showing the bucket opened; Fig. 3 is a side elevation, showing my invention in slightly modified form; Fig. 4 is a perspective view of the bucket illustrated in Fig. 3; Figs. 5, 6, 7, and 8 are diagrammatic illustrations of further modifications of my invention; Fig. 9 is a partial plan view of my bucket, equipped with compound-leverage opening-devices, desired in certain uses; Fig. 10 is a detail side view of the devices shown in Fig. 9; and Fig. 11 is a diagrammatic view showing a cable and sheaves which constitute an equivalent of the device shown in Fig. 9.

My device is particularly intended and adapted for handling coal, ore, and other heavy bulk material. Devices of its class commonly comprise two scoops or bucket portions adapted to form a single receptacle when their cutting edges are brought together. When such a bucket is lowered the scoops are separated or opened, and in this opened condition they are dropped upon the loose material and by reason of their weight sink into the same. Force is then applied to raise the bucket and this force is so exerted as to first result in causing the scoops to dig into the material and to close together therein, thereby inclosing a load of material. In this condition the loaded bucket is elevated and usually conveyed to a distant point, where the load is deposited by opening the bucket. This general construction and the foregoing method or manner of operation are preserved in my invention; but I have been able to markedly simplify the construction of my bucket and operating mechanism, compared with the devices and apparatus in present use.

In lieu of scoops or bucket portions which are connected by the numerous pivotal joints heretofore considered necessary in a wide opening bucket, I employ two simple rigid bucket portions, each attached to a common frame by a single pivot. Thus at once it will be seen that my invention possesses several advantages over others.

A further distinctive feature of my invention as better explained hereinafter, resides in separating the pivots of the two scoops or bucket portions a considerable distance, whereby a bucket of great spread is secured within small vertical dimensions. The use of this single feature results in great simplification of the structure.

A further distinctive feature of the invention, which will be noted at once upon reference to the drawings, resides in an arrangement of hoisting cables, which permits and enables the bucket to be swung or turned by mere manipulation of said cables, a simple laterally movable trolley or truck being substituted by me in place of the complicated, rotary bull wheel or turn table and trolley, with mechanism for oper-

95

90

100

105

ating the same, ordinarily employed for the purpose, the need therefor being dispensed with.

Referring now to the drawings for details of construction and particularly to Figs. 1 and 2, it will be seen that my novel grab bucket, irrespective of the operating part, comprises only three members, to-wit; a frame A, and two scoops or bucket portions, B-B. The frame A comprises two side members a-a, and three shafts a'-a'-a², suitable means (not shown) being usually employed for securing shafts in place. The shafts a'-a' are the pivots for the scoops B-B and in this form of my bucket said scoops are rigidly secured to respective shafts, to turn therewith as hereinafter described. The shaft a² is preferably fixed in the plate a-a and carries the differential winding mechanism hereinafter described. If desired each scoop may be made from a single piece of heavy sheet metal, but as the lower portions are subjected to the greatest wear, I prefer to make them of heavier material than the upper portions which less frequently require repairs. For this reason each scoop is shown to be composed of a heavy lower portion B and two lighter, upper portions b', the latter connected by a cross bar b². The pivots of the scoops are widely separated in the frame a, and the middle or meeting portions of the scoops underhang respective shafts a'. The bucket when closed, as in Fig. 1, is very low, that is, it is of little height, compared with present-day grab buckets of like capacity; yet when opened, as shown by dotted lines in Fig. 2, the scoops have a disproportionately or greatly increased reach or spread, by reason of the separation of the pivots at their tops. The advantage of the low bucket is that it may be readily worked beneath the cross girders or deck beams in ships; furthermore the low bucket may be worked from a lower track or boom. The bucket by reason of its small size may also be made of less weight than others. When closed together the scoops or halves B-B form a single bucket, capable of holding several tons of coal or ore.

For opening the bucket, I employ cables C-C, having their lower ends attached to cranks arm D-D fixed on respective shafts a'-a', or if desired the cables may be secured directly upon the sides of the scoops or bucket members B-B, other cross bars like unto b² being used in such cases (see Fig. 5). Obviously the attachment of the cables directly to the scoops is equivalent to attachment to the arms, D-D, inasmuch as said arms are rigidly connected to respective scoops B-B through the medium of the shafts a'-a'.

In the absence of a force tending to elevate the frame a, the weight of said frame plus the weight of the parts carried thereby, plus the weight of the upper or inner ends of the members B-B, is sufficient to cause the descent of the inner ends of the scoops when relieved from the closing force, said weight overbalancing the lower portions of the scoops; hence the suspension of the bucket wholly by the cables C-C causes the opening of the bucket, as shown by dotted lines in Fig. 2. b²-b² represent pairs of toothed intermeshing gears or segments, on the shafts a'-a', and hence rigidly connected with the members B-B. These connect the two scoop or bucket portions B-B and serve to equalize their movements, preventing the unequal opening or closing thereof.

I may employ a single cable C for each side or member of the bucket, but Fig. 1 discloses the preferred arrangement, comprising duplicate cables C', connected to respective arms D. In places where it is unnecessary to turn or swing the bucket, I use a single pair of cables C, but in all other cases, I employ the two pairs of cables C-C and C'-C', as shown in Figs. 1 and 4, such duplication of the cables adapting the bucket to be swung or turned with great ease, as better explained hereinafter.

As before stated the winding or closing mechanism is arranged on the shaft a². It comprises a roller having small portions E', and a large portion E², whereon the closing cables or chains E³-E³, and the hoisting cable E are respectively wound. The ends of the short draft cables E³ are secured to the small portions or hubs E' of the winding pulley and their outer ends are fastened in the cross bars, b', or directly to the sides of the scoops as may be desired. The turning of the pulley on the shaft a², either releases the members, B, or draws them together. This in drawing or closing force is exerted on the pulley E² by means of the main hoisting cable E, wound once or more about the large pulley E², and fastened thereon. The cables E and E³ are wound in opposite directions on the pulley and its hubs and the difference in diameter provides sufficient leverage to forcibly wind the draft cables on the smaller pulleys or drums and thereby close the scoops B with great digging power. The operation is clearly shown by the dotted and the full lines of Fig. 2. The closing and hoisting effort is exerted on the cable E, while the cables C-C and C'-C' are slack. The slack of the cable E having been withdrawn from pulley E², and the members B-B having been closed together, the pulley E² is held against further rotation by the cables E³-E³, after which the pulley E² serves simply as an anchor or fastening for the cable, and further pull on the cable E elevates the bucket bodily. It will be noted that the cable E is located centrally in the bucket, passing over a central sheave, or through an eye E⁴, provided in the frame piece a², and loosely attached to the shafts a'-a'. From the moment that the members B-B are closed together, the cables C-C may also be drawn taut to assist in raising the bucket. Obviously the dumping of the loaded bucket may be accomplished at any time by slackening the central cable E, and holding the other cables, thereby leaving the bucket suspended by cables C-C or C'-C'; or by holding the closing line and pulling on the opening cables C-C.

It should be noted that the winding or closing mechanism of my grab bucket occupies a definite, unchanging position with respect to the pivots of the scoops. Being located beneath said pivots and between said scoops it is obvious that when force is exerted therethrough to close the open bucket, the winding mechanism will remain substantially stationary and cause the scoops to dig deeply into the material, their movement being downward beneath the drum of the winding mechanism. The effectual loosening and digging of even closely packed, heavy material, such as iron ore, is thus insured, actual power being added to the weight of the bucket, to drive the scoops downward.

The means that I prefer for carrying the bucket and for moving the same laterally comprise a plurality of

pulleys or sheaves mounted on a boom or a track F and a trolley G movable thereon. The boom and trolley shown in the drawings (Fig. 1) are typical only; that is, I have not attempted to illustrate the details of the structure, inasmuch as in carrying out my invention, any movable member provided with properly positioned sheaves, will serve the purpose, however supported. The essential elements of this movable member or trolley (which with the two pairs of cables C—C and C'—C') 5 enables me to dispense with the usual rotary bull wheel or turn table) are the central sheave GE and the four sheaves GC—GC and GC'—GC' or their equivalents. The main central cable E passes up over the sheave GE and thence back to the hoisting drum. The sheaves or 10 pulleys GC—GC are arranged at a distance from GE and substantially parallel therewith, to accommodate the cables C—C. The pulleys GC' may be in line with the pulley GE, but are revoluble independently. The quartering or relatively perpendicular arrangement of 15 the sheaves GC—GC and GC'—GC', with the cables thereon makes it possible to swing the bucket by the mere manipulation of the pairs of cables, C—C and C'—C'; that is, the cable, E, being central within the bucket furnishes an axis about which the bucket may 20 be turned or twisted, while suspended thereby, and the cables, C—C and C'—C' supply the means for thus turning or twisting the bucket. As stated the cables, C—C and C'—C', pass over the quartered sheaves on the trolley and the bucket being in suspension upon the 25 central cable, E, may be readily turned by slackening and tightening the two pairs of opening cables. Thus when the cables, C—C, are drawn taut and when the cables, C'—C', are slackened the arms D of the bucket naturally follow the cables, C—C, until positions directly beneath the pulleys, GC—GC, are reached. 30 This condition is illustrated in Fig. 1 by full lines. An opposite condition is indicated by the dotted lines of Fig. 1, a condition brought about by tightening the cables C'—C' and slackening the cables C—C, thereby 35 partially suspending the bucket from cables C'—C', and causing the bucket to turn and swing into the plane thereof. It will be obvious that the bucket may be turned into and held in various intermediate positions, with respect to the trolley, by exerting simultaneous 40 but different twisting strains on the bucket through the medium of the pairs of cables C—C, C'—C'. The bucket may be turned into either of its forty-five degree positions with relation to the planes of the pairs of sheaves, by equalizing the movements of the pairs of cables on 45 their sheaves.

Instead of using a movable trolley as above described, I may fix the sheaves GC—GC and GC'—GC' and GE directly to the boom or other member of the derrick, crane or other device used for operating the bucket.

50 I have not deemed it necessary to illustrate the hoisting mechanism proper, as my invention admits of the employment of almost any well known hoisting engine equipped with a suitable number of winding drums.

For some uses, particularly in working in the holds of 55 vessels, I find it desirable to confine all of the hoisting cables to a single vertical plane, parallel to the pivots of the scoops. In such cases I may dispense with the arms D on the shafts at the top of the bucket and in place thereof employ arms B⁴, directly upon the scoops 60 b'; the arm or arms B⁴ of one scoop or member b' ex-

tending beneath the pivot shaft of the other member, as shown in Figs. 3 and 4. The large winding drum or differential pulley E', the central hoisting cable E, and the draft cables E³—E³ remain as before described, but the cables C—C and C'—C' are passed through eyes or 70 over sheaves at A⁴, located at points between the shafts and near the sides of the bucket, so that all of the cables are confined to a single plane midway between the upper or pivot shafts of the bucket. The lower ends C⁴ of the cables C—C, C'—C' are in this case passed around 75 small sheaves C⁷ on the shaft a², and thence upward to respective arms B⁴. Each cable draws on one of said arms B⁴, hence when the bucket is sustained by either pair thereof, the arms B⁴ will be drawn down to the positions shown by dotted lines in Fig. 3 and the bucket 80 will be opened. One or more pairs B⁴ of gear segments serve to equalize the movements of the members b'. The duplicate cables of the bucket shown in Figs. 3 and 4, pass upwardly over a movable member, boom or trolley, exactly as described in connection with 85 Fig. 1, and it will be obvious that as the draft or pull of the opening cables, is exerted upon the bucket at points distant from its central vertical axis, said bucket may be caused to swing or turn quite as readily as the previously described bucket. I also operate this grab 90 as a two line grab, when it is not necessary to turn grab, by splicing the opening lines or cables together at points beyond the trolley or directly above the bucket into one line; thus having one opening and one closing line. The grab buckets shown in Figs. 1, 95 2, 3, and 4 may be operated as two, three, or five line grabs to suit the particular hoisting machinery used or specified by the purchaser. Where it is not necessary to operate the grab as a twisting grab I use only one pair of opening or outlying cables, making three in all with 100 the central cable. For heavy or special service any or all the cables may be duplicated.

Various modifications of my invention, as thus far described, will readily suggest themselves to one skilled in the art. Certain of these which relate to 105 the draft or winding mechanism, whereby the scoops are closed, are shown diagrammatically in Figs. 5, 6, 7, and 8. In Fig. 5, I have illustrated a modification of the invention wherein a single hoisting cable I is attached to a winding drum I', within the bucket, and 110 other cables H, passing over a sheave H' on one member B, cross thence to fastenings H'' on the other member. The hoisting effort of the cable I by turning drum I' winds up the cables H on the small drums and thus forcibly draws the scoops together.

In Fig. 6, a cross bar J and links J'—J' are employed to connect the members B—B with the hoisting cable drum K. The rotation of this drum either opens or closes the scoops.

In Fig. 7 I have illustrated a form of my invention 120 wherein the central hoisting cable L, directly performs the work of closing the bucket, being attached to one of the members, and wound about sheaves L' on both members.

Fig. 8 illustrates the employment of a segment of a 125 gear M as a means of rotating the small winding drum M', whereto the draft cables M'' are attached. The simple leverage of the opening cables, effected upon the scoops through the medium of the arms D or B⁴, or as indicated in Fig. 5, is sometimes insufficient to 130

insure the opening of the bucket; particularly where the closing cable overhauls a heavy drum or when the grab bucket is working in pasty or sticky material which does not readily free itself from the bucket when the latter is opened. In such cases I prefer to compound the leverage between the opening cables and the bucket, in the manner shown in Figs. 9 and 10, or by an equivalent mechanism shown in Fig. 11. The compound leverage devices shown in Figs. 9 and 10, each comprise two gear segments G^1 and G^2 , the former having a segment on which the opening cable C is secured and being loose on its shaft, while the segment G^2 is keyed to its shaft a^1 . This device is duplicated, two gears G^1 and G^2 being provided for each half of the bucket. The gear portion of G^1 is about one-half the radius of the part G^2 , hence the purchase or leverage of the cable C upon the opposite bucket member or scoop is doubled, as compared with the arrangement shown elsewhere in the drawing. The effectiveness of the weight of the central portion of the bucket is thus doubled in the opening operation. A similar effect is secured by the construction shown in Fig. 11, whereby the type of bucket shown in Fig. 4 is employed. In this case the arm B^4 is provided with a sheave and the opening cable is passed downward beneath the shaft a^1 , and thence upward over the sheave on the arm B^4 , obviously increasing the purchase between the frame A and the member B .

I desire that it shall be understood that the initial 30 and if desired the maximum hoisting effort may be exerted upon the outer cables, and the opening of the bucket controlled by the central cable, quite as effectively as with the reverse arrangement of the cables, described herein. And as to the swinging or manipulation of the bucket by means of said outer cables, the particular functions which the cables are required to perform within the body of the bucket in nowise affect their function exterior thereto. Either arrangement of the cables, if employed with the diagonal or quartering arrangement of cables or sheaves on the boom or trolley, allows the bucket to be turned by regulating the tension of the cables in the manner hereinabove described.

As still further modifications of my invention are known to me and will be perceived by others, I do not confine my invention to the specific structures herein shown and described.

Having thus described my invention, I claim as new and desire to secure by Letters Patent:

50 1. The improvements herein described, comprising, in combination, a grab bucket composed of a frame, separated pivots thereon, scoops mounted on said pivots respectively, scoop opening and closing means including suitable cables, certain of said cables ending from a point or points distant from the vertical axis of the bucket, and laterally movable but otherwise relatively fixed quartering sheaves for said cables whereby the bucket may be opened and closed and turned by manipulating said cables, substantially as described.

60 2. The improvements herein described, comprising, in combination, a grab bucket, a laterally movable support, a plurality of cable sheaves mounted thereon, and bucket opening cables, passing over said sheaves, two of said cables being attached to and extending from a single point on said bucket, distant from the vertical axis thereof, and passing over separate sheaves on said support, for turning or twisting the bucket, substantially as described.

3. The improvements herein described, comprising a grab bucket, in combination with opening, and closing hoisting-cables therefor and suitable laterally movable, 70 but otherwise relatively fixed, cable carriers or sheaves quarteringly arranged above the bucket, and at least two of said cables extending from a single point on the bucket over two of said sheaves, substantially as and for the purpose specified.

4. The improvements herein described, comprising a plurality of cable sheaves, in combination with a laterally movable, non-rotative support for said sheaves, a grab bucket, cables whereby said bucket is suspended from said sheaves and said sheaves, said cables and said bucket being so related, that said bucket may be turned by slackening and tensioning said cables, substantially as described.

5. The improvements herein described, comprising a laterally movable support, in combination with a cable sheave centrally mounted thereon, other sheaves also mounted thereon and spaced about the first mentioned or central sheave, a grab bucket, a central operating cable whereon the bucket is suspended from said central sheave and a pair of operating cables each on its own sheave and extending to a single, non-central point upon the bucket, whereby said cables aid the suspension of said bucket and by which the bucket may be turned or twisted, substantially as described.

6. The improvements herein described, comprising a laterally movable support, in combination with a central cable sheave mounted thereon, other sheaves also mounted thereon and spaced about the first mentioned or central sheave, a grab bucket, a central operating cable whereon the bucket is suspended from said central sheave, and two pairs of operating cables, each pair extending from a single, non-central point upon the bucket whereby the bucket is suspended from said spaced sheaves, substantially as described.

7. The improvements herein described comprising a frame, in combination with widely separated pivots thereon, substantially triangular scoops mounted on respective pivots and adapted to close beneath said frame, and suitable scoop opening and closing means including hoisting cables, substantially as described.

8. The improvements herein described, comprising a grab bucket composed of a frame, in combination with scoops having their upper ends pivotally attached to said frame, the pivotal axes of the scoops being separate thereon, and suitable scoop operating means provided upon said frame, beneath said pivots, substantially as described.

9. The improvements herein described comprising a frame, in combination with separate scoop pivots thereon, two scoops having their upper ends fixed upon respective pivots, scoop closing means connecting said scoops beneath said frame and hoisting and operating cables for opening and closing said scoops and hoisting the device as a whole, substantially as described.

10. The improvements herein described, comprising a frame, in combination with bucket portions, independently pivoted on said frame and widely separated thereon, but adapted to close together at the bottom to complete a grab bucket, means for opening said bucket and differential winding and hoisting means extending between and connecting said scoops beneath said frame, substantially as described.

11. The improvements herein described, comprising a grab bucket, having opening and closing members, in combination with means for sustaining and hoisting said bucket and a cable adapted to aid in sustaining and hoisting said bucket, the lower end of said cable being attached to the bucket at a point distant from the vertical axis thereof, whereby relatively lateral tension may be exerted to rotate the bucket on said axis, substantially as described.

12. The improvements herein described, comprising a grab bucket having opening and closing members, in combination with a central operating cable, pairs of non-central operating cables, a suitable laterally movable support and sheaves thereon, one for each of said cables, substantially as described.

13. The improvements herein described, comprising a

- grab bucket, composed of a frame, in combination with rigid scoops, having their upper ends pivoted thereon, a winding or closing mechanism inclosed within and by said scoops, opening cables attached to respective scoops, and another operating cable attached to said closing means, substantially as described. 80
14. The improvements herein described, comprising a frame, in combination with scoops separately and distantly pivoted apart thereon, closing or winding means on said frame beneath the scoop pivots, an operating cable for each scoop and an operating cable common to said scoops, connected to the same and said frame through the medium of said winding means, substantially as described. 85
15. The improvements herein described, comprising a frame, in combination with a winding mechanism thereon, scoops pivoted on said frame above said winding mechanism, an operating cable extending between the pivots of the scoops and attached to said operating means and other operating cables connected to respective scoops, substantially as described. 90
16. The improvements herein described, comprising a frame, in combination with scoop closing or winding means in the lower part of said frame, single member scoops adapted to close beneath said frame and having their upper ends distantly pivoted separately thereon at points widely apart and above said winding means and suitable operating cables connected with said winding means and said scoops, substantially as described. 95
17. The improvements herein described, comprising a frame, in combination with closing or winding means thereon, scoops adapted to close beneath said winding means and separately pivoted to said frame at different points above said winding means and suitable equalizing means joining said scoops, substantially as described. 100
18. The improvements herein described, comprising a frame, in combination with single member scoops adapted to close beneath said frame and having widely separated upper ends pivotally mounted upon said frame, opening cables connected to respective scoops and a closing cable suitably connected to both scoops at points within the same, substantially as described. 105
19. The improvements herein described, comprising a frame, in combination with scoops separately pivoted on said frame and adapted to close beneath the same, an equalizer connecting said scoops, opening cables, compound leverage devices connecting the same with respective scoops and a closing cable connected with both scoops, substantially as described. 110
20. The improvements herein described, comprising a frame, in combination with shafts therein, scoops arranged on respective shafts and adapted to close beneath said frame, equalizing means connecting the upper ends of said scoops, scoop opening arms or levers, a winding mechanism mounted in said frame beneath said shafts and connected with said scoops and suitable hoisting cables, substantially as described. 115
21. The improvements herein described, comprising a frame, in combination with a differential winding mechanism thereon, scoops pivoted on said frame above the winding mechanism and adapted to close together beneath the winding mechanism, substantially as described. 120
22. The improvements herein described, comprising a frame, in combination with a differential winding mechanism thereon, the scoops pivoted on said frame above said winding mechanism and adapted to close together beneath said winding mechanism, an equalizer connecting said scoops and compound leverage devices connected with said scoops for opening the same, substantially as described. 125
23. The improvements herein described, comprising a suitable trolley, in combination with a central sheave thereon, other sheaves quartered about the same on the trolley, a grab bucket, pairs of cables extending from said bucket over the quartered sheaves on the trolley and a central cable extending from the bucket over said central sheave, substantially as described. 130
24. The improvements herein described, comprising a frame, in combination with scoops having their upper ends
- pivoted thereon, differential closing means on the frame beneath the scoop pivots, suitable opening cables connected with respective scoops and a closing cable connected with said closing means, substantially as described. 135
25. The improvements herein described, comprising two scoops, each a single rigid member, in combination with means pivotally joining the upper ends of said scoops, a suitable equalizer, scoop opening cables connected with respective scoops and a central closing cable connected with both scoops at points below the upper ends thereof, substantially as described. 140
26. The improvements herein described, comprising two scoops, each a single rigid member, in combination with means pivotally joining the upper ends of said scoops, a suitable equalizer, pairs of scoops opening cables connected with respective scoops and a central closing cable connected with both scoops at points below the upper ends thereof, substantially as described. 145
27. The improvements herein described, comprising two scoops, each a single rigid member, in combination with means pivotally joining the upper ends of said scoops, a suitable equalizer and non-coincident sheaves, one for each cable, said scoop opening cables connected with respective scoops and a central closing cable connected with both scoops at points below the upper ends thereof, substantially as described. 150
28. The improvements herein described comprising a frame, in combination with substantially triangular scoops, an equal number of pivotal shafts in said frame whereon the upper ends of the scoops are mounted, said scoops being adapted to close beneath said frame, scoop closing means provided in the frame beneath said shafts and opening and closing cables attached to said scoops and to said closing means respectively, substantially as described. 155
29. The improvements herein described, comprising a frame, in combination with a plurality of shafts therein, substantially triangular scoops, each mounted on one of said shafts, such pivotal shafts and the upper ends of said scoops being widely separated, a winding mechanism arranged in said frame beneath said shafts for closing said scoops and hoisting cables attached to said winding mechanism and to respective scoops; substantially as described. 160
30. In a device of the class described, a substantially triangular frame, in combination with a pair of scoops having their upper ends pivoted therein, differential closing means on said frame beneath the scoop pivots, an arm rigidly connected to each said scoop, a pair of cables attached to the outer end of each said arm and adapted to open said scoop and turn the same on its vertical axis, and a combined closing and hoisting cable connected to said differential closing means, substantially as described. 165
31. In a device of the class described, a suitable frame, in combination with a pair of scoops having their upper ends pivoted therein, equalizing means connecting the upper ends of said scoops, differential closing means on said frame, an arm rigidly connected to each said scoop, a pair of cables attached to each said arm and adapted to open said scoop and to turn the same on its vertical axis and a hoisting cable, connected to said differential closing means, substantially as described. 170
32. In a device of the class described, a suitable frame, in combination with a pair of shafts mounted in said frame, co-acting scoops having their upper ends mounted on respective shafts, differential closing means inclosed by said scoops beneath said shafts, opening cables suitably connected with respective scoops, and a central cable connected with and actuating said differential closing means, substantially as described. 175
33. In a device of the class described, a suitable frame, in combination with a pair of shafts mounted in said frame, co-acting scoops mounted on said shafts, equalizing means connecting said scoops, differential closing means mounted upon said frame, suitable opening cables connected with respective scoops, and a closing cable connected with said closing means, substantially as described. 180
34. In a device of the class described, a suitable frame, in combination with a pair of shafts mounted in said frame, co-acting scoops mounted on said shafts, differential closing means, a pair of cables connected with each said

35. In a device of the class described, a suitable frame, in combination with a pair of shafts mounted in said frame, a pair of co-acting scoops mounted on said shafts, intermeshing segmental gears on said shafts, differential closing means upon said frame, opening cables and a closing cable, substantially as described. 75
35. In a device of the class described, a suitable frame, in combination with a pair of shafts mounted in said frame, a pair of co-acting scoops mounted on said shafts, intermeshing segmental gears on said shafts, differential closing means upon said frame, opening cables and a closing cable, substantially as described. 80
- 10 36. In a device of the class described, a suitable frame, in combination with a pair of shafts mounted in said frame, a pair of co-acting scoops mounted on said shafts, an arm rigidly secured to each said shaft, suitable opening cables connected with said arms, differential closing means mounted upon said frame and a suitable hoisting cable connected therewith, substantially as described. 85
- 15 37. In a device of the class described, a suitable frame, in combination with a pair of shafts mounted in said frame, a pair of co-acting scoops mounted on respective shafts, an arm rigidly secured to each said shaft, a pair of cables attached to each arm and adapted to open respective scoops and to turn the device as a whole, differential closing means mounted upon said frame, and a closing cable, substantially as described. 90
- 20 38. In a device of the class described, a suitable frame, in combination with a pair of scoops pivoted on said frame, equalizing means connecting said scoops, a movable support above said frame, a cable sheave centrally mounted thereon, differential scoop closing means mounted in said frame, a hoisting cable attached to said closing means and passing over said sheave, other sheaves mounted upon said support and arranged quartering about said central sheave, an arm secured to each said scoop and a pair of cables attached to each said arm and passing over separate sheaves upon said support, substantially as and for the purpose described. 95
- 25 39. The improvements herein described, comprising a laterally movable support, in combination with three sheaves mounted thereon, a grab bucket having a central closing cable extending over the middle sheave on said support and two cables extending over the other sheaves and attached to the members of said bucket for opening the same, substantially as described. 100
- 40 40. The improvements herein described, comprising a grab bucket composed of scoops, in combination with a closing mechanism, a central scoop closing cable, scoop opening cables attached to respective scoops and suitably positioned sheaves for said cables, substantially as described. 105
- 45 41. The improvements herein described comprising a frame, in combination with substantially triangular scoops, an equal number of pivotal shafts whereby the upper ends of the scoops are attachable to said frame, said scoops being adapted to close beneath said frame, scoop closing means and opening and closing cables attached to said scoops and to said closing means respectively, substantially as described. 110
- 50 42. The improvements herein described, comprising a frame, in combination with substantially triangular scoops each pivoted to the frame by a single shaft, such pivotal shafts being widely separated, a winding mechanism for closing said scoops and hoisting cables attached to said winding mechanism and respective scoops, substantially as described. 115
- 55 43. In a device of the class described, a substantially triangular frame, in combination with a pair of scoops having their upper ends pivoted therein, differential closing means beneath the scoop pivots, an arm rigidly connected to each said scoop, a pair of cables attached to the outer end of each said arm and adapted to open said scoop and turn the same on its vertical axis, and a combined closing and hoisting cable connected to said differential closing means, substantially as described. 120
- 60 44. In a device of the class described, a suitable frame, in combination with a pair of shafts mounted in said frame, a pair of co-acting scoops mounted on said shafts, intermeshing segmental gears on said shafts, differential closing means, opening cables and a closing cable, substantially as described. 125
- 65 45. In a device of the class described, a suitable frame, in combination with a pair of shafts mounted in said frame, a pair of co-acting scoops mounted on said shafts, an arm rigidly secured to each said shaft, suitable opening cables connected with said arms, differential closing means and a suitable hoisting cable connected therewith, substantially as described. 130
- 70 46. In a device of the class described, a suitable frame, in combination with a pair of scoops pivoted on said frame, equalizing means connecting said scoops, a movable support above said frame, a cable sheave centrally mounted thereon, differential scoop closing means mounted in said frame, a hoisting cable attached to said closing means and passing over said sheave, other sheaves mounted upon said support and arranged quartering about said central sheave, an arm secured to each said scoop and a pair of cables attached to each said arm and passing over separate sheaves upon said support, substantially as and for the purpose described. 135
- 75 47. The improvements herein described, comprising a frame, in combination with scoops separately pivoted on said frame and adapted to close beneath the same, opening cables, compound leverage devices connecting the same with respective scoops and a closing cable connected with both scoops, substantially as described. 140
- 80 48. The improvements herein described, comprising a frame, in combination with a differential winding mechanism thereon, the scoops pivoted on said frame above said winding mechanism and adapted to close together beneath said winding mechanism, and compound leverage devices connected with said scoops for opening the same, substantially as described. 145
- 85 49. The improvements herein described, comprising two scoops, each a single rigid member, in combination with means pivotally joining the upper ends of said scoops, scoop opening cables connected with respective scoops and a central closing cable connected with both scoops at points below the upper ends thereof, substantially as described. 150
- 90 50. The improvements herein described, comprising two scoops, each a single rigid member, in combination with means pivotally joining the upper ends of said scoops, pairs of scoop-opening cables connected with respective scoops and a central closing cable connected with both scoops at points below the upper ends thereof, substantially as described. 155
- 95 51. The improvements herein described, comprising two scoops, each a single rigid member, in combination with means pivotally joining the upper ends of said scoops, and non-coincident sheaves, one for each cable, said scoop opening cables connected with respective scoops and a central closing cable connected with both scoops at points below the upper ends thereof, substantially as described. 160
- 100 52. In a device of the class described, a rigid frame, in combination with a pair of scoops having their upper ends directly pivoted upon said frame, differential closing means beneath the scoop pivots, an arm extending from each said arm, an opening cable for each arm, and a combined closing and hoisting cable connected to said differential closing means, substantially as described. 165
- 105 In testimony whereof, I have hereunto set my hand, this 1st day of November, 1906, in the presence of two subscribing witnesses.
- HERMAN P. ANDRESEN.
